UNITED STATES PATENT OFFICE.

WERNER ZEINDLER, OF PHILADELPHIA, PENNSYLVANIA, ASSIGNOR OF ONE-HALF
TO GEORGE L. GAY, OF PHILADELPHIA, PENNSYLVANIA.

REFRIGERATING APPARATUS.

Application filed January 2, 1920. Serial No. 343,743.

To all whom it may concern:

Be it known that I, WERNER ZEINDLER, a citizen of Switzerland, residing at Philadelphia, in the county of Philadelphia and State of Pennsylvania, have invented new and useful Improvements in Refrigerating Apparatus, of which the following is a specification.

My invention relates to a new and useful improvement in refrigerating apparatus, and has for its object to provide an exceedingly simple and effective device of this description the working parts of which are entirely inclosed and having a distended refrigerating coil which may be readily inserted in a refrigerator or ice chest of any design and effect the cooling of the interior thereof without the necessity of using ice.

A further object of my invention is to so construct the apparatus that the maximum efficiency for extracting the heat from the cooling agent in its cycle is obtained and to expose the maximum cooling surface for refrigerating purposes relative to the amount of cooling agent used.

A still further object of my invention is to so design the apparatus that the working parts will be entirely contained within the central compartment while the circulating and cooling water surrounds this compartment, to dispose the compressing cylinder in a vertical position and to provide direct drive for the mechanism from a housed motor so that the apparatus may be entirely self contained and readily lubricated by the splash system.

A further object of my invention is to provide a secondary suction valve which will act as the intake from the central chamber so as to withdraw any gas which may leak thereto from the compressing cylinder.

A further object of my invention is to so construct the suction valve and its connective parts as to prevent it from falling into the compressing cylinder should the parts thereof become displaced or disarranged from accident or wear.

A still further object of my invention is to provide for making ice in limited quantities while effecting the cooling of the ordinary refrigerator box.

With these ends in view, this invention consists in the details of construction and

combination of elements hereinafter set forth and then specifically designated by the 55 claim.

In order that those skilled in the art to which this invention appertains, may understand how to make and use the same, I will describe its construction in detail, referring 60 by numerals to the accompanying drawings forming a part of this application, in which:-

Fig. 1, is a vertical section of a refrigerating apparatus showing the motor and refrigerating coil in elevation.

Fig. 2, is an enlarged fragmentary view showing the compressing cylinder and valve casings in plan.

Fig. 3, is a section at the line 3-3 of 70 Fig. 2.

Fig. 4, is a detail view of the suction valve casing.

Fig. 5, is a similar view of the suction valve stem and split washer therefor.

Fig. 6, is a section view of a household refrigerator showing my improved refrigerating apparatus applied thereto.

Fig. 7, is a detail plan view of the ice making element.

In carrying out my invention as here embodied, 1 represents a jacket preferably circular in cross section in which is located the casing 2 the latter being of such diameter as to form a compartment between 85 the walls of the jacket and the walls of said casing for containing the water which serves to cool the system.

The interior of the casing 2 provides a compartment for housing the operating 90 mechanism and in this compartment is located the compressor cylinder 3 in which latter operates the piston 4 connected by the pitman 5 to the crank shaft 6. This crank shaft is journaled in the bearings 7 and 95 carries a beveled gear 8 meshing with the beveled pinion 9 the latter being secured upon the vertical shaft 10. The lower end of this vertical shaft is mounted in the bearing 11 while the upper portion thereof passes through the long bearing 12, said shaft carrying a beveled gear 13 upon its upper end with which meshes the beveled pinion 14 carried by the shaft 15 of the motor 16. By this arrangement when the 100 motor is in operation the crank shaft will

be revolved causing the piston to reciprocate within its cylinder.

To the upper end of the cylinder is fitted the head 17 and in this head is fitted the suction or intake valve casing 18 having the valve seat 19 at the lower end thereof upon which the suction valve 20 is adapted to seat. This casing is held in place by the threaded plug 21 having a depending shank 22. The valve 20 is provided with a stem 23 the upper portion of which is hollow as indicated at 24 and has formed therewith a collar 25 between which and the bottom of the casing 18 is interposed the coil spring 26 for the purpose of normally holding the valve 20 upon its seat. The valve stem 23 also has formed therewith the flange 27 beneath which the split washer 28 is placed, said washer being of such diameter as to contact with the flange 29 formed upon the interior of the casing 18 by which arrangement the stem is free to move up and down within the casing within certain limitations and this washer will prevent the valve from falling into the cylinder should the collar or spring break.

The hollow portion 24 of the stem telescopes over the shank 22 so as to guide the stem in its reciprocating movements.

20 The valve casing 18 has two openings 30 and 31 formed in the sides thereof the opening 30 registering with the intake 32 while the hole 31 registers with the secondary intake 33, and 34 represents a spring pressed 25 valve which normally closes the intake opening 35 communicating with the interior of the casing 2 for the purpose hereinafter set forth.

36 represents the exhaust valve which is 40 fitted in a suitable casing, set in the head 17 and communicating with the cylinder and from this valve leads the passageway 37 to which the upper end of the pipe 38 is secured. This pipe is coiled around the casing 2 out of contact therewith so as to have its entire surface subjected to the action of the cooling water contained in the compartment outside of the casing.

The lower end of the pipe 38 passes 50 through a stuffing box 39 and is connected with the expansion valve 40, said valve in turn being connected with the upper end of the refrigerating coil 41, the lower end of said coil being turned upward through the 55 center of the coil as indicated at 42 and terminating in the control valve 43. This control valve is connected with the pipe 44 which passes upward therefrom into the interior of the casing 2 and is connected with 60 the intake passageway 32.

From the foregoing description the operation of my improved apparatus will be as follows:—

The system being charged by the introduction of the proper amount of said cooling

agent into the coils 38 and 41 through the control valve 43 the motor in operation the reciprocations of the piston 4 will draw the cooling agent in gaseous form into the cylinder through the pipe 44 and the suction 70 valve and then compress the same forcing it out into and through the coil 38 which when reaching the expansion valve 40 will be liberated in the form of gas into the coil 41 thus lowering the temperature of said coil 75 to the proper degree and this cycle will continue as long as the motor is in operation, the coil 38 and its contents being constantly cooled by the water contained in the compartment between the jacket and the casing, 80 said water being supplied through the proper surface line connected to the inlet 45 and a circulation of said water maintained by the connection drain line with the outlet 46.

In practice the apparatus when so placed upon a refrigerator or ice box with the coil 41 projects into said box as clearly illustrated in Fig. 6 and when the apparatus is in operation as above described this refrigerating coil will produce the proper temperature within said box.

47 represents a brine tank which may be placed within the refrigerator and in which 95 is a secondary coil 48 leading from the refrigerating coil 41 having a valve 49 located in said secondary coil by which arrangement the placing of a can 50 within the brine tank to cause the freezing of the contents of said can, and by filling said can with 100 water a block of ice may thus be produced.

51 represents a hood which is placed over the beveled gears 13 and 14 to inclose the same and provide against possible accident. When the apparatus is in operation any 105 leakage of the cooling agent from the cylinder through the piston or otherwise will pass into the central compartment to prevent the loss of the same or its interference with the operations of the machine, the same will be sucked back into the cylinder by the action of the piston through the secondary valve 35 thus preventing the loss of the cooling agent from the system thereby increasing the economy. By my improved construction a cheap, simple and efficient refrigerating apparatus is provided which may be readily applied to any refrigerator and is especially adapted for application to 110 household refrigerators.

115 Of course I do not wish to be limited to the exact details of construction as herein shown as these may be varied within the limits of the appended claim without departing from the spirit of my invention.

Having thus fully described my invention, what I claim as new and useful is:—

120 In a refrigerating apparatus, the combination of a casing, a jacket surrounding said casing and spaced therefrom to form a

compartment for the circulation of water, a coil disposed in said compartment and enclosing the casing, a cylinder within the casing with which said coil communicates, valves controlling the communications between the coil and cylinder, a secondary valve forming a communication between one

of the first named valves and the interior of the casing, and a piston reciprocatingly mounted in the cylinder.

In testimony whereof, I have hereunto affixed my signature.

WERNER ZEINDLER.
